UNITED STATES PATENT OFFICE.

WILLIAM E. COOK, OF NEW YORK, N. Y.

COLLECTING MECHANISM FOR CARDING-MACHINES.

1,312,953.

Specification of Letters Patent.

Patented Aug. 12, 1919.

Application filed November 20, 1917. Serial No. 202,953.

To all whom it may concern:

Be it known that I, WILLIAM E. COOK, a subject of the King of the United Kingdom of Great Britain and Ireland, residing at

5 St. George, in the borough of Richmond, city of New York, county of Richmond, and State of New York, have invented certain new and useful Improvements in Collecting Mechanisms for Carding-Machines, of 10 which the following is a specification, reference being had therein to the accompanying drawings, which form a part thereof.

My invention relates to collecting mechanisms for carding machines, and more particularly to a supporting structure for the containers in which the sliver is spirally wound, and to a particular form of container adapted to coöperate with this structure.

20 Collecting mechanisms of the character to which my invention relates, have heretofore embodied therein a rotatable container having a false bottom acted upon by a supporting spring. The sliver was 25 delivered to this container by a suitable winding device carried by the cover of the container, the sliver being more or less compacted within the container as the result of the thrust of said supporting spring toward 30 the cover. As the sliver accumulates in the container, the false bottom will gradually be depressed by the incoming sliver until the container is filled. This condition results in the development of a variable gradually increasing pressure upon the sliver in 35 the container, which I have found to develop more or less undesirable conditions in the contents of a container when the sliver is used in other machines particularly in ma-

40 chines for applying this sliver to conductor wires as a covering of insulating material therefor. This mechanism for collecting the sliver has a further disadvantage that after the container has been completely filled, it 45 is necessary to dump the coil of sliver therefrom into another, and larger, container which disturbs the uniformity of the coil, and has a tendency to entangle and mat portions of the sliver to a degree which interferes with the rapid withdrawal of the sliver 50 from the container to which it is transferred.

A collecting mechanism made in accordance with my invention is designed to have cotton sliver coiled in a rotating container 55 under conditions which will prevent a grad-

ual increase of the pressure exerted upon the coil, and preserve more or less, the uniformity of the pressure to which the coil is subjected. The container itself when completely filled, may be removed from the 60 carding machine to its operative relation with other machines for treating or utilizing the sliver, thus avoiding the necessity for transferring the contents of the container into which the sliver is delivered by the 65 carding machine to a second and larger container; and eliminating all possibility of entangling or matting the sliver during this transfer, or as the result of the expansion of the coil in the container to which it is 70 transferred.

A machine made in accordance with my invention may be so constructed as to absolutely control the maximum pressure exerted upon the sliver, after its delivery to 75 the container, it being possible to so regulate this mechanism as to practically eliminate this pressure if desired.

In a machine made in accordance with my invention, I use a container having a false 80 bottom supported by a plunger forming a permanent part of the collecting mechanism structure, this plunger being so supported as to prevent any such binding thereof as will develop such frictional resistance to its 85 free movement as might vary the pressure conditions as to the sliver within the container. I so construct the machine as to eliminate friction, wherever possible, in the parts acting upon and appurtenant to this 90 plunger so as to insure absolute freedom of movement of the plunger.

A mechanism made in accordance with my invention is so constructed as to avoid any possibility of the support for the false bottom 95 of the container interfering with the proper coiling of the sliver, and resultant entangling or matting of different strands of the sliver within the container.

The container itself is adapted to be removed from the supporting structure to permit the mounting of an empty container thereon, and as a matter of convenience I provide means whereby the plunger, which has a normal thrust toward the top of the 100 container, may be lowered to the full extent to facilitate the mounting of a container upon its support, or its removal therefrom.

The invention consists primarily in a collecting mechanism for carding machines 110

embodying therein a rotatable support for a container, a reciprocating plunger projecting through said support and adapted to project within and support a movable false bottom of a container upon said support, and means acting upon said plunger whereby substantially uniform resistance is offered to the depression of said plunger, and in such other novel features of construction and combination of parts as are hereinafter set forth and described and more particularly pointed out in the claims hereto appended.

Referring to the drawings:

15 Figure 1 is a view showing one element of a collecting mechanism, partly in elevation and partly in section;

20 Fig. 2 is a diagrammatic view of the supports for the containers and the actuating means therefor, and

25 Fig. 3 is a detail view of the connection between the support and the plunger.

Like letters refer to like parts throughout the several views.

30 25 In the accompanying drawings, I have shown merely a collecting mechanism, with its associated containers mounted upon two of the rotating supports, the delivery mechanism by means of which the sliver is coiled within said containers being omitted because such is old and well known in this art and has no new and useful functions by reason of the structure of the collecting mechanism.

35 35 In the embodiment of my invention shown in the drawings, the main frame of the machine which is adapted to be situated within a pit adjacent the delivery end of a carding machine, is shown as being composed of top and bottom plates *a* and *b* suitably connected and spaced apart by means of vertical, parallel guide rods *c*. Suitably mounted upon the top plate *a* is a plurality of supports *d* each of which carries a gear *e*. 40 40 Each support *d* is preferably provided with a peripheral flange as shown, and any desired number of said supports may be employed. The various gears *e* are entrained by means of intermediate, idler gears *e'*, all 45 50 of said gears being simultaneously driven from a gear *f* upon a power shaft *f'*, and an idler intermediate gear *f''* connected with one of the intermediate gears *e'* in order to secure the desired speed of rotation of the 55 several supports *d*.

60 60 The guide bars *c* are arranged in pairs, below the supports *d* respectively, each bar of said guides having slidably mounted thereon, a traveler block *g* having suitable bearings *g'-g''* coöperating with said guides. Connected to the opposite sides of each traveler block *g*, by means of flexible connections *h* passing over pulleys *h'* on the underside of the top plate *a*, are weights *h²*.

Rotatably mounted upon the traveler 65 block *g* is a plunger *i*, having an enlarged bearing *i'* at the lower end thereof, suitable antifriction devices being disposed between the bearing and the traveler block *g*. The brackets *g³* upon said block serve to hold 70 said plunger *i* in relation to said block.

The plunger *i* extends through the support *d*, the upper end thereof being provided with a table head *i²* adapted to support the false bottom *j'* of a container *j*, 75 which container has an opening in the bottom thereof of sufficiently great diameter to permit the passage of said table head and an inwardly directed flange of sufficient width to prevent the escape of the bottom *j'* there- 80 through.

The plunger *i* is slidably mounted in relation to its coöperating support *d*, while receiving a rotary movement therefrom. While the desired coöperation of the support 85 *d* and the plunger *i* might be secured by means of an ordinary spline or feather, I have found in practice that to avoid the development of pressure upon the sliver within the container in excess of that predetermined by the adjustments of this mechanism, it is essential to provide an anti-friction connection between the support *d* and the plunger coöperating therewith. I have also found it necessary to provide a balanced 90 95 condition, upon opposite sides of said plunger to avoid binding between it and the support. In order to minimize possibility of binding at this point, I provide the plunger *i*, at diametrically opposite points there- 100 of, with key ways as shown in Fig. 3, the depth of which is sufficient to receive the roller bearings *k* mounted upon suitable pintles *k'* secured to the support *d*. This structure is made possible because the power 105 required to turn the plunger *i* is very small, and the ball bearings between the bearings *k* and the traveler block *g* eliminate frictional resistance to the rotary movement of said plunger.

110 The weights *h²* normally overbalance the aggregate weight of the traveler block *g*, and plunger *i* and its appurtenances so as to impart a normal upward thrust to said plunger, or offer sufficient resistance to its 115 downward movement under the control of the coiled sliver, to secure the desired compaction of this sliver. To facilitate the regulation of this resistance to that required, I form the weights *h²* as cups loaded with shot 120 or other small removable particle. In this manner it is possible to apply substantially the same power, or resistance, to diametri- 125 cally opposite points of the support *d* and thus insure a substantially parallel move- ment of this block.

The delivery mechanism coiling the sliver within the container *j* forms a part of the

carding machine and in order to facilitate the mounting of empty containers in relation to this mechanism, and the removal of said containers when filled, it is desirable 5 to provide some convenient method of overcoming the load of the weights h^2 during this operation. This result I secure, by providing a flexible connection m , one end of which is exposed above the top plate a and the other end of which is connected with the bottom of the traveler block g after said connection has passed about a pulley n mounted between the guide rods c upon the bottom plate b .

15 While in the accompanying drawings, I have shown a collecting mechanism consisting of a gang of four supports d and their appurtenances, it is apparent that the number of said supports is immaterial to 20 the invention, and may be varied to accord with the requirements of any particular carding machine. In the drawings, I have not duplicated the showing of the plunger i and its coöperating parts, since 25 each of these mechanisms is identical with every other and has exactly the same mode of operation.

In describing the operation of the collecting mechanism, I will also limit the 30 description of the functions of one support d and its appurtenances.

The frame a and b and guide rods c are positioned in a pit adjacent the delivery end of a carding machine with the supports 35 d in axial alinement with the cover for the containers j carried by said carding machine. The support d is continuously rotated from the carding machine actuating mechanism. When it is desired to mount 40 a container j upon a support, the traveler block g is pulled downwardly by means of the cord or chain m and the container j with the false, or movable, bottom therein is mounted upon the supports d within the 45 flange thereof. This mounting of the container positions the table head i^2 within the bottom of the container in contact with the bottom j' thereof. When the container has been thus positioned on the support d , the 50 cord or chain m is released thus permitting the weights h^2 to raise the block g and position the bottom j' adjacent the top of said container.

Power is then applied to the carding machine thus causing rotation of the support d .

As the cotton sliver is delivered within the container j upon the bottom j' thereof, the movement of the said bottom to accommodate this sliver, is resisted by the 60 weights h^2 , the resistance, however, not being sufficiently great to cause a substantial compact or matting of the fibers of the sliver. With the continuous operation of the carding machine, and the gradual accumulation 65 of the sliver, in the form of a coil,

within the container j , the plunger i will continue to descend without any increase in the resistance from the weights h^2 to this movement, there being in fact a slight diminution of this resistance due to the weight 70 of the accumulated sliver resting upon or acting against said bottom j' . The effect of the gradual augmentation upon the load of said bottom is minimized somewhat, however, by the slight friction developed 75 between the outer surface of the coiled sliver and the inner wall of the container j so that there will be a substantially uniform resistance to the downward movement of the bottom. If the plunger i were to 80 bind upon the support d , a condition would develop in which the pressure exerted upon the contents of the container would be materially increased and thus result in excessive compaction of the coils of the sliver, 85 within the said container. It is for this reason that I use the roller or ball bearings k and the roller bearings between the bearing i' and the guide block c , this latter arrangement minimizing the friction between 90 the said roller or ball bearings k and the walls of the key way in the plunger i .

By the construction described, I secure in a more or less crude mechanism delicacy of adjustment which in practice has given 95 very satisfactory results. The weights h^2 do little more than positively overbalance the load of the block g and plunger i and its appurtenances, thus practically limiting the compacting pressure upon the sliver to that 100 developed by the frictional resistance encountered by the coil at the inner wall of the container.

It is desired to emphasize that when the container is filled to its utmost capacity the 105 pressure exerted upon the sliver therein by the plunger i is no greater than that exerted upon the first bight of the sliver laid upon the bottoms j' and in fact would probably be gradually lessened as the container fills. 110

When the container is filled, the ordinary attachments used in carding machines, will stop the said carding machine and with it the support d , ordinary carding machine attachments also serving to stop this mechanism in the event of the breakage of the sliver.

When the container is completely filled, it is merely necessary to raise the cover in the usual manner and remove the container j 120 with its contents from the supports d and transport it to the proper relation with the machine in which the sliver is further treated or utilized.

By reason of the uniform conditions under 125 which the sliver is laid in the container, I have found that the sliver may be readily withdrawn therefrom without those inconveniences or delays resulting from the matting of the fibers of different layers of the 130

sliver, or from unequal density of different portions of the coil. This condition permits the rapid withdrawal of the sliver and avoids losses of time in the subsequent handling of 5 the sliver.

In covering wires with sliver, I have found that the covering machine may be run at high speed without likelihood of breakage of the sliver as the result of resistance to 10 the withdrawal thereof from the container, thus avoiding frequent breakages of the sliver and resultant irregularities in the density of different portions of the insulating material upon the wire.

15 It is not my intention to limit the invention to the precise details of construction shown in the accompanying drawings, it being apparent that such may be varied without departing from the spirit and scope of 20 the invention.

Having described the invention, what I claim as new and desire to have protected by Letters Patent is:—

1. A collecting mechanism for carding 25 machines, embodying therein a rotatable support for a container, an open bottom container removably mounted upon said support, a false bottom movably mounted in said container, a reciprocatory plunger projecting through said support and adapted to 30 project within and support said movable false bottom, and means acting upon said plunger whereby substantially uniform resistance is offered to the depression of said 35 plunger.

2. A collecting mechanism for carding 40 machines embodying therein a rotatable support for a container, an open bottom container removably mounted upon said support, a false bottom movably mounted in said container, parallel guides below said support, a traveler block slidably mounted on said guides, a reciprocatory plunger rotatably mounted upon said traveler block, 45 projecting through, slidably mounted in, and rotatable with said support and adapted to project within, and support said movable false bottom, and a weight acting upon said traveler block whereby substantially 50 uniform resistance is offered to the depression of said plunger.

3. A collecting mechanism for carding 55 machines embodying therein a rotatable support for a container, an open bottom container removably mounted upon said support, a false bottom movably mounted in said container, parallel guides below said support, a traveler block slidably mounted on said guides, a reciprocatory plunger rotatably mounted upon said traveler block, 60 projecting through, slidably mounted in and rotatable with said support and adapted to project within, and support said movable false bottom, and a plurality of balanced 65 weights acting upon opposite sides of said

traveler block, whereby substantially uniform resistance is offered to the depression of said plunger.

4. A collecting mechanism for carding 70 machines embodying therein a rotatable support for a container, an open bottom container removably mounted upon said support, a false bottom movably mounted in said container, parallel guides below said support, a traveler block slidably mounted on said guides, a reciprocatory plunger rotatably mounted upon said traveler block, 75 projecting through, slidably mounted in, and rotatable with said support and adapted to project within, and support said movable 80 false bottom, and a plurality of balanced, adjustable weights acting upon opposite sides of said traveler block, whereby substantially uniform resistance is offered to the depression of said plunger.

5. A collecting mechanism for carding 85 machines embodying therein a rotatable support for a container, an open bottom container removably mounted upon said support, a false bottom movably mounted in 90 said container, parallel guides below said support, a traveler block slidably mounted on said guides, a reciprocatory plunger projecting through, slidably mounted in, and rotatable with said support and adapted to 95 project within, and support said movable false bottom, an anti-friction bearing between said plunger and said traveler block, means holding said plunger in relation to said block, and a plurality of weights acting 100 upon opposite sides of said traveler block, whereby substantially uniform resistance is offered to the depression of said plunger.

6. A collecting mechanism for carding 105 machines embodying therein a rotatable support for a container, a reciprocatory plunger projecting through said support and adapted to project within and support a movable false bottom of a container upon said support, said plunger having a key way therein, 110 an anti-friction member carried by said support and seated in said key way whereby said plunger rotates with, and is slidable in relation to, said support, and means acting upon said plunger whereby substantially 115 uniform resistance is offered to the depression of said plunger.

7. A collecting mechanism for carding 120 machines embodying therein a rotatable support for a container, a reciprocatory plunger projecting through said support and adapted to project within and support a movable false bottom of a container upon said support, said plunger having diametrically opposite key ways therein, a 125 roller bearing seated in each of said key ways and pintles upon which said bearings are mounted, carried by said support, whereby said plunger rotates with, and is slidable in relation to, said support, and 130

means acting upon said plunger whereby substantially uniform resistance is offered to the depression of said plunger.

8. A collecting mechanism for carding machines embodying therein a rotatable support for a container, a reciprocatory plunger projecting through said support and adapted to project within and support a movable false bottom of a container upon said support, means acting upon said plunger whereby substantially uniform resistance is offered to the depression of said plunger, and means whereby said plunger may be drawn downwardly to permit the mounting of a container in said support.

9. A collecting mechanism for carding machines embodying therein a rotatable support for a container, parallel guides below said support, a traveler block slidably mounted on said guides, a reciprocatory plunger rotatably mounted upon said traveler block, projecting through, slidably mounted in, and rotatable with said support and adapted to project within and support a movable false bottom for a container upon said support, a weight acting upon said traveler block, whereby substantially uniform resistance is offered to the depression of said plunger, and a pull cord attached to the bottom of said traveler block,

passed about a pulley and exposed adjacent said support, whereby said plunger may be drawn downwardly to permit the mounting of a container upon said support.

10. A collecting mechanism for carding machines embodying therein a rotatable support for a container, a reciprocatory plunger projecting through said support and adapted to project within and support a movable false bottom of a container upon said support, means acting upon said plunger whereby substantially uniform resistance is offered to the depression of said plunger, in combination with a container adapted to be mounted in said support, having an open bottom through which said plunger may project, and a movable bottom adapted to be supported by said plunger whereby a filled container may be removed from said support to a mechanism for further treating or utilizing the sliver.

In witness whereof, I hereunto affix my signature, in the presence of two subscribing witnesses, this 14th day of November, 1917.

WILLIAM E. COOK.
